UNITED STATES PATENT OFFICE.

THOMAS CATCHINGS HOLLIDAY, OF CANTON, MISSISSIPPI.

TIRE-TOOL.

1,268,071.

Specification of Letters Patent. Patented May 28, 1918.

Application filed November 4, 1916. Serial No. 129,466.

To all whom it may concern:

Be it known that I, THOMAS CATCHINGS HOLLIDAY, a citizen of the United States, and a resident of Canton, in the county of 5 Madison and State of Mississippi, have invented a new and Improved Tire-Tool, of which the following is a full, clear, and exact description.

It is well known that a headless tack or 10 the like, embedded in a tire, if not located and removed after it has produced a puncture, will produce successive punctures. An important object of my invention is to provide a tool having the general character of 15 a scraper, adapted to be passed over the interior surface of the tire casing and which will unfailingly locate an embedded tack, pin, or other puncturing substance while at the same time the scraper will be effective 20 in clearing the inner surface of the casing by loosening up and removing sand or other matter adhering thereto and which, when permitted to remain on the casing, not infrequently results in what is known as sand 25 punctures.

A further object of the invention is to provide a resilient curved scraper device which, when applied to the casing with scraping pressure, will accommodate itself 30 to the radii of tires of different sizes.

The distinctive character of the improved tool whereby the foregoing objects are attained will clearly appear from the specific description following.

35 Reference is to be had to the accompanying drawings forming a part of this specification in which similar reference characters indicate corresponding parts in both views.

40 Figure 1 is a side elevation of a tire tool constructed in accordance with my invention;

Fig. 2 is an elevation taken at right angles to Fig. 1.

45 In carrying out my invention in accordance with the illustrated example, a bowed member 10 in the form of a flat, resilient metallic strip is supported at its ends on divergent resilient arms 11 and preferably 50 is formed integral with said arms.

The side arms 11 are flattened and taper toward their inner convergent ends as indicated at 12, Fig. 2. The flattened side arms are integral with round rods 13 due to the 55 device being formed of a round rod, flattened to produce the resilient members 10,

11 and returned on itself, the round portions of the rod being twisted together to constitute a handle 13.

In operating on the interior of a casing, 60 the bowed member 10 is disposed transversely of the casing and caused to exert a scraping action thereon. The resiliency of the member 10 and the arms 11 will permit of these members yielding so that the bowed 65 element may conform to a casing of greater radii than the normal radii of said element. It will be obvious that upon being passed over the inner surface of the casing, the contacting side edge of the bowed member 70 10 will serve to engage any protruding or embedded tack or the like so that the latter is readily located. Also, it will be clear that the inner surface of the casing may be thoroughly cleaned by loosening and scraping 75 off any adhering sand or other matter, thereby preventing sand punctures.

The drawings show pincer jaws 14 on the handle normally in close relation at their end portions as at 15, but these are 80 not claimed in the present application.

Having thus described my invention I claim as new and desire to secure by Letters Patent:

1. A tool of the class described including 85 a handle, a resilient scraper element of thin, plate-like material disposed transverse to the axis of the handle and presenting broad front and back surfaces substantially perpendicular to the general plane of the tool, 90 said element being flexible in the said plane and non-yielding in a transverse plane, the opposite edges of the bowed element being in the form of narrow dull scraper edges, and resilient members connected with the 95 handle and with the bowed element at the ends only thereof to be responsive to a yielding of the said element in the plane of the tool, said resilient connecting members being flattened and tapering from the bowed 100 element toward the handle.

2. A tool of the class described including a handle, resilient arms on the handle at the front end and diverging therefrom, and a bowed resilient element united at its ends 105 with the forward end of said arms, said bowed element being flat, presenting arcuate scraper edges, and the arms being flattened and tapering from the bowed element toward the handle.

3. A tool of the class described including 110 a rod returned on itself, and united to form

a handle, the intermediate portion of the said rod being flattened, forming a resilient bowed front end having arcuate scraper edges at opposite sides and flattened side arms integral with said bowed elements, said arms converging from the bowed element to the handle.

a resilient bowed element, and a handle substantially perpendicular to the said bowed element and flexibly connected therewith at both ends of the latter, the opposite edges of the said bowed element being in the form of narrow dull scraper edges.

4. A tool of the class described including

THOMAS CATCHINGS HOLLIDAY.
